UNITED STATES PATENT OFFICE.

WILLIAM C. BUCK, OF PETERBOROUGH, CANADA.

ECCENTRIC-CHAIN LIFT-PUMP.

SPECIFICATION forming part of Letters Patent No. 696,624, dated April 1, 1902.

Application filed June 7, 1901. Serial No. 63,583. (No model.)

To all whom it may concern:

Be it known that I, WILLIAM C. BUCK, a subject of the King of Great Britain, residing at Peterborough, county of Peterborough, 5 Province of Ontario, Canada, have invented certain new and useful Improvements in Eccentric-Chain Lift-Pumps; and I do hereby declare that the following is a full, clear, and exact description of the invention, such as 10 will enable others skilled in the art to which it appertains to make and use the same.

My invention relates to improvements in eccentric-chain lift-pumps; and among other things I have in view the provision of means 15 for operating the plunger-rod with comparative ease, to provide means for effecting an increase or decrease in the lifting power of the lever, so that the operating mechanism may be adapted to deep or shallow wells, to 20 provide means for taking up slack in the operating parts and to assist in forcing down the plunger-rod, to provide means by which the plunger-rod may be arranged for nearly its 25 entire length outside of the education-pipe, to simplify and cheapen the manufacture of the pump-cylinder, and to provide an improved type of valved plunger.

To the accomplishment of these ends my invention consists in the novel construction, arrangement, and combination of parts, 30 which will be hereinafter fully described and claimed.

In the accompanying drawings, forming a part of this specification, Figure 1 is a side 35 elevation of my improved pump. Fig. 2 is a horizontal section through the plunger-operating mechanism, taken in the plane of the dotted line 22 on Fig. 1. Fig. 3 is a vertical cross-section in the plane of the dotted line 40 33 on Fig. 1. Fig. 4 is a detail view, in side elevation, of the shiftable power-wheel.

The same numerals of reference denote like parts in each of the several figures of the drawings.

45 34 designates a base-plate having a collar 34^a, within which is arranged the education-pipe, and from this base-plate rises a pair of standards 35, the lower ends of which are securely bolted to the base-plate, as at 35^a. 50 These standards are arranged parallel to the

education-pipe 29, and they are connected thereto by means of the horizontal bars or plates 36, the latter being employed in pairs, as shown more clearly by Fig. 3. Each pair of plates or bars have the outer ends thereof 55 curved at 37 to partially embrace the education-pipe 29, and said curved ends of the bars are drawn together and clamped firmly upon the pipe by the bolt 38.

40 designates the power-wheel, comprising 60 a rim having one or more grooves 41, according to the number of chains which it may be desired to use, and this power-wheel is provided with a web or plate 42, which is cast in a single piece with the grooved rim, said web 65 having a wide diametrical slot 43 and other narrower slots 44, as shown more clearly by Fig. 5. The power-wheel is arranged in a vertical position between the upper ends of the standards 35 and the upper pair of bars or 70 plates 36, and between the plates or bars 36 and the side faces of this power-wheel are interposed the plates 45 46. Said plates have lateral engagement with the power-wheel, and they are secured thereto by the transverse 75 bolts 47 47^a, the same passing through the slots 44 in the web of the power-wheel.

48 designates the fulcrum-bolt, which is secured firmly in the upper ends of the standards 35 and the outer ends of the upper pair 80 of bars 36, and this fulcrum-bolt extends loosely through a block or bushing 49, the latter being slidably fitted in the wide slot 43 of the power-wheel and interposed between the plates 45 46, as clearly shown by Figs. 2 and 3. 85

50 designates the operating-lever, which is fitted against one face of the power-wheel and is secured thereto by the bolts 51, thus making the lever fast with the power-wheel, so that these parts will turn together on the axis 90 afforded by the fulcrum-bolt 48.

52 designates a short length of chain, which is fitted in one of the grooves 41 of the power-wheel and has its upper end secured by a bolt 53 to the lugs 54 of the power-wheel. The 95 other end of the chain is connected to a hook 55, that is secured or clamped firmly to the plunger-rod 18, as shown by Fig. 1, thus operatively connecting the power-wheel and the plunger-rod together.

55^a designates a guide which is clamped, as at 56, to the upper extremity of the plunger-rod 18, and through this guide is loosely arranged the shank 57 of a hook 58, the latter 5 having a nut 59, arranged to afford a seat for the upper end of a take-up spring 60, said spring being loosely fitted on the stem 57 and seated upon the guide 55^a. To the hook 58 is connected the upper end of a length of 10 chain 61, the same being fitted in a second groove 41, provided in the rim of the power-wheel, and the lower end of said chain being secured by a bolt to a lug 62, which is provided on the power-wheel, as shown.

15 The energy of the spring 60 holds the chain 61 in a taut condition, so as to take up the slack in the parts of the operating mechanism, and as the chain 61 is coiled around the power-wheel in an opposite direction to the chain 52 20 it is evident that this spring normally exerts tension on the two chains, because it acts through the power-wheel, and thereby prevents any slack from occurring in either of the chains, notwithstanding the wear to which 25 the parts are subjected.

As shown by Fig. 1, the power-wheel occupies a concentric relation to the fulcrum-bolt 48, and this arrangement allows the lever 50 to be easily operated, so as to lift the plunger-rod 18 when strain is imposed upon the 30 chain 52 by movement of the lever and the power-wheel in the direction indicated by the arrow in Fig. 1. This relative disposition of the parts is advantageous under some circumstances—as, for instance, when the pump is used in shallow wells—but I find it desirable to increase the lifting power of the lever when the pump is used in deeper wells. Under these conditions the nuts on the fulcrum-bolt 48 are slackened, as well as the bolts 47 47^a, and this allows the power-wheel to be adjusted into eccentric relation to the bolt 48, because the power-wheel may be drawn outwardly from the eduction-pipe, whereby the 40 slotted part 43 of the power-wheel may move on the bolt 48 and the block 49, while the slotted parts 44 of the power-wheel have movement with relation to the bolts 47 47^a. The power-wheel may thus be adjusted within the 45 limits of the slots 43 44, so as to increase the leverage exerted by the power-wheel on the chain 52 and the plunger-rod. I have also thought it advisable under some circumstances to employ the auxiliary operating 50 mechanism which is shown by Fig. 1. A treadle-lever 63 is fulcrumed at 64 to the frame, said lever having a series of apertures 65, in either of which may be fitted a pin or bolt 66 in order to adjustably connect a pitman 67 to said treadle-lever, the latter having the foot-loop 68. An intermediate perforated lever 69 is fulcrumed at 70 to the standards, and to it is adjustably connected a second link 71, which has shiftable connection 60 by a pin 72 with the perforated part 73 of the

hand-lever 50. It is evident that the operator may apply foot-pressure to the treadle-lever 63, the movement of which is transmitted through the links and intermediate lever to the hand-lever 50, thereby augmenting the 70 power which may be applied by the hand and foot to the plunger-rod.

It will of course be understood that the eduction-pipe and the plunger-rod are carried downwardly below the pump-platform, so that 75 they may be operatively related to a submerged cylinder and a piston which is arranged for operation in said cylinder; but as these parts may be of any preferred construction or of any character known to those 80 skilled in the art I have not considered it necessary to illustrate or to describe the same.

Charges within the scope of the appended claims may be made in the form and proportion of some of the parts, while their essential features are retained and the spirit of the invention is embodied. Hence I do not desire to be limited to the precise form of all the parts as shown, reserving the right to vary therefrom.

Having thus described my invention, what I claim as new is—

1. In a pump, the combination with a plunger-rod and a suitable framework, of a power-wheel provided with a slotted web, plates fastened adjustably to the slotted web, a fulcrum-bolt extending through the slotted web and the plates and supported in the framework, and a chain attached to the power-wheel and connected to the plunger, substantially as described.

2. In a pump, the combination with a plunger-rod and a suitable framework, of a power-wheel having a slotted web, plates applied to opposite sides of the web and connected by bolts which pass through certain slots in the web, a fulcrum-bolt passing through the plates and another slot in the web of the power-wheel and attached to the framework, and a chain attached to the power-wheel and connected to the plunger-rod, substantially as described.

3. In a pump, the combination with a plunger-rod and a suitable framework, of a power-wheel having a diametrical web provided with the central and side slots, plates applied to opposite sides of the web to span the slots therein, the bolts passing through the side slots in the web and fastening the plates adjustably to the power-wheel, a fulcrum-bolt passing through the plates and the central slot in the web of the power-wheel and attached to the framework, and a chain attached to the power-wheel and connected to the plunger-rod, substantially as described.

4. In a pump, the combination with a plunger-rod, of a power-wheel, a chain attached to the power-wheel and to the plunger-rod, a yieldable link slidably supported on the plunger-rod above the point of attachment of said

chain thereto, a cushion-spring operatively connected to the yieldable link, and a second chain attached to the yieldable link and to the power-wheel, substantially as described.

5. In a pump, the combination with a power-wheel, a plunger, of a chain connected to the power-wheel and the plunger, a spring-actuated link supported by the plunger-rod, and

another chain connected to the link and the power-wheel, substantially as described. ¹⁰

In witness whereof I have hereunto set my hand in the presence of two witnesses.

WILLIAM C. BUCK.
